[57] CLAIM

The ornamental design for a bird receiver for live poultry mover, as shown and described.

DESCRIPTION

FIG. 1 is a top plan view of a bird receiver for live poultry mover showing my new design, it being understood that the design has been broken away in the middle to indicate indeterminate length;

FIGS. 2 and 3 are opposite side elevational views thereof with the exterior frame and transparent panels omitted so as to illustrate the interior roller and belt assembly;

FIGS. 4 and 5 are opposite perspective views of the roller and belt assembly thereof on a reduced scale with the exterior frame and transparent panels being omitted for convenience of illustration;

FIGS. 6 and 7 are opposite end elevational views thereof; and

FIGS. 8 and 9 are opposite side elevational views thereof.
